UNITED STATES PATENT OFFICE

EUGENE L. BAKER, OF TAUNTON, MASSACHUSETTS

STOVE BOTTOM

Application filed September 25, 1928. Serial No. 308,234.

Household stoves of a known kind, are provided with a bottom having a moulding which is exposed between the body of the stove and the base of the stove. The moulding has to be enameled, in order to be presentable, and although there is no occasion for enameling the bottom, it has to be enameled along with its moulding, because it is not commercially feasible to enamel the moulding and not the bottom that carries it. The present invention aims to reduce expense by doing away with the exposed moulding, so that the moulding and the bottom will not have to be enameled, novel means being provided whereby the body of the stove may be connected directly to the base, the edge of the bottom being concealed.

Figure 1 is an elevation showing part of a stove in which the invention is embodied; 20 and Figure 2 is a sectional detail.

The body 1 of the stove has an outstanding lip 2 provided with a depending flange 3 equipped with lugs 4 having slots 5 for the reception of securing elements 6, such as bolts, engaged with hollow bosses 9 on the inclined portion 8 of the bottom 7 of the stove, the bottom having a transverse reinforcing rim 10 within which the depending flange 3 of the body 1 is received. The upper edge of the rim 10 bears against the lower surface of the body 1, and the lower edge of the flange 3 bears against a narrow web 11 that joins the part 8 of the bottom 7 to the rim 10. The legs 12 fit in the angle 30 formed by the lip 2 and the rim 10 and so do the sections 14 of the base. The sections 14 of the base have wings 15 that extend behind the legs 12, the wings being connected to the legs by bolts 16 or the like. The legs 12 and the members 14 may be alluded to generally as the "base."

The bottom 7 has no exposed moulding, and the objects set forth in the opening portion of this specification thus are consummated. Moreover, the structure shown in Figure 2 makes a strong connection between the body, the base, and the bottom.

Having thus described the invention, what is claimed is:—

50 A stove comprising a body having an out-

standing lip provided at its inner edge with a depending flange, a base extended beneath the lip, the inner edge of the base and the lower surface of the lip forming an angle, a bottom having an incline and a transverse 55 reinforcing rim within which the depending flange of the body is received, the upper portion of the rim being seated snugly in said angle, in contact with the inner edge of the base and in contact with the lower surface 60 of the lip of the body, the rim being concealed within the base, and means for connecting the bottom to the body.

In testimony that I claim the foregoing as my own, I have hereto affixed my signature. 65
